UNITED STATES PATENT OFFICE.

WILLIAM S. GODWIN, OF BALTIMORE, MARYLAND.

PAVING-GUARD.

1,324,391.

Specification of Letters Patent.

Patented Dec. 9, 1919.

Application filed November 5, 1917. Serial No. 200,304.

To all whom it may concern:

Be it known that I, WILLIAM S. GODWIN, a citizen of the United States, residing at Baltimore, State of Maryland, have invented certain new and useful Improvements in Paving-Guards, of which the following is a specification.

This invention relates to improvements in roadways generally, and more particularly to a paving guard for roadways having asphaltic surfaces.

While, as above stated, the invention relates particularly to a paving guard for roadways, the roadway is, to some extent, in accordance with my invention, so constructed as to coöperate with the guard in accomplishing the purposes of the invention.

In roadways of this character, especially those very generally and extensively constructed in suburban and rural districts, in which there is a base of concrete, macadam or gravel, and a bituminous surface, or surface of bricks or blocks, the roadway is made or paved to loose stone shoulders, or to plank or the concrete base on the sides is extended up to the surface level of the roadway, forming, with the latter method, a smooth concrete edge. These sidings or edges, having for their purpose to limit or define the width of the roadway, have proven very unsatisfactory, as the traffic soon wears away the edges of the roadway and there being no support for the paving it disintegrates, becomes ragged, and merges into the loose dirt of the side of the road, resulting in the destruction of the road on the sides and requiring constant and expensive repairs.

The object of this invention is to overcome those objections, which I do by providing a metallic guard generally in the form of an angle-iron, extending longitudinally along the roadway for the entire distance or length thereof, the guard being anchored at suitable intervals in the base of the roadway, which, according to the character of the roadbase, may be of concrete, broken stones or gravel, as to form the necessary bed to retain the anchor, and thereby the guard, and to support the surface of the roadway adjacent to the edges, whether said surface be of the monolithic type, such as a bituminous layer, or blocks or bricks.

A further object of the invention is to provide a thoroughly practical, durable and economical construction--particularly eco-

nomic when the saving in the expense incident to repairs is considered.

A still further object is to provide, in cases where the guard is employed in connection with a roadway having a surface of bricks or blocks, a means for permitting slight lateral expansion of the roadbed, as will appear from the illustrations and the description.

In the drawings,

Fig. 1 is a section of a portion of a roadbed, showing the road constructed with a macadam base, and a bituminous surface.

Fig. 2 is a similar view showing the guard used in connection with a roadway having a bituminous surface, and base of macadam and concrete.

Fig. 3 is a similar view showing a section of a roadway in which the base is entirely of concrete.

Fig. 4 is a similar view of a portion of a roadway, in which the surface is formed of blocks or bricks.

Fig. 5 is a perspective view of a section of the preferred form of guard, showing the manner of cutting the same out to form the anchor;

Fig. 6 is a transverse section of the guard taken about on line $\alpha-\alpha$ of Fig. 5 showing the manner of bending down the cut section to form the anchor.

Fig. 7 is a modification of the guard showing the anchor made in a separate piece, and attached to the guard proper.

Fig. 8 is a top plan view of still another modification of the guard made in serpentine form and riveted to the guard proper at intervals in its convolutions.

I have only illustrated a section of roadway, where the surface is of blocks or bricks, in which the base is of macadam, or may be of gravel, but it will be understood that in constructing a roadway of this type, the entire base may be of concrete, like that shown in Fig. 4.

Referring to the drawings, the numeral 1 designates the main portion of the roadway, which, in the main, may be constructed with the usual macadam or gravel base 2, illustrated as macadam in the present instance. In my construction, this base may extend for the entire width of the road, or it may be stopped short of the entire width, and in its place, I may provide a concrete body 2', flush at the top with the macadam or gravel foundation, but extending consider-

ably below the base at the bottom, as indicated at 3. This concrete also extends somewhat beyond the roadway proper as indicated at 4, thus forming a substantial foundation for the metallic guard 5, which is formed of angle irons of appropriate and convenient length, arranged end to end and extending longitudinally along the roadway, there being a guard formed of such sections 10 on each side of the road. The angle-irons are formed with a vertical flange 6 and horizontal flange 7, the vertical flange being of suitable depth for retaining the surface of the roadway, and the horizontal flange being 15 of a depth suitable for providing the anchors at intervals throughout the guard sections.

The numeral 8 designates a bituminous or asphaltic surface of the roadway of the monolithic type, the base or foundation for 20 which being formed of macadam. The bituminous surface is filled in flush with the upper edge of the vertical part of the guard, as shown.

In the type of roadway illustrated in Fig. 25 4 the numeral 9 designates paving blocks of any suitable character. When these are used upon the bases illustrated, either entirely of concrete or gravel, or of gravel alone, there is filled in upon the base, a stratum or layer 30 of sand 10, and in this, the blocks are embedded. In this form, it will be noted, the vertical portion of the guard is considerably longer than the horizontal portion, to accommodate the depth or thicknesses of the 35 blocks and interposed between the outer series of blocks and the inner faces of the guard, is a plate of bituminous material such as asphalt or tar, or other compressible material 11, to permit of lateral expansion and 40 contraction of the surface.

The form of guard I prefer is illustrated in Fig. 5 in which the material of the horizontal flange is cut out at intervals, as indicated at 12, and bent first downwardly at 45 right angles to the flange, and then laterally to form anchors 13, the lower ends of the anchors being sharply bent to form angle pieces 14, for the purpose of getting a better hold or lock in the base for the purpose of 50 anchoring the guards firmly in place. This is probably the most economical way to form anchors the same being integral with the body proper of the guard, but, as shown in the modification in Fig. 7, the anchors may 55 comprise a member 15 originally flat, but bent to form an overlapping end 16 by which it may be riveted or welded to the horizontal portion of the guard, and twisted so as to bring a portion of its lower edge to a position 60 at right angles to the main body of the member, as indicated at 17, the anchor of this form being like the anchor first described, bent sharply at its lower end, as indicated at 18, for better hold in the base.

65 In the modification shown in Fig. 8, the

numeral 19 designates the anchor which may be made from a flat strip bent at intervals to form flat bearing surfaces 20, through which may extend rivets 21, the material between these points being twisted and bent downwardly for a hold in the base adjacent to the sides of the roadway.

In Fig. 3, I have shown the base of the road as made entirely of concrete, but I desire it understood that my invention does 70 not reside in the fact of continuing the concrete base entirely across the roadway, it being only essential to my purposes, in whatever type of roadway I may construct, that the base be of a character to firmly retain 75 the anchors, and thereby the guards.

Having thus described my invention, what I claim is:

1. A metallic guard for defining the longitudinal edges of roadways, said guard 80 having an upwardly extending portion, forming a boundary for the upper edges of the roadway, said guard having also a laterally extending integral flange remote from its upper edge and cut longitudinally at intervals, the cut portions being bent downwardly and outwardly to form anchors, said anchors at their lower ends being bent approximately at right angles, said anchors being adapted to hold the guards in place.

2. In a roadway, in combination, a metallic guard having an upwardly extending portion extending to the surface of the roadway and forming a boundary for the surface, said guard having also a laterally extending integral flange remote from its upper edge and cut longitudinally at intervals, the cut portions being bent to form anchors for holding the guards in place.

3. A metallic guard for defining the longitudinal edges of roadways, said guard having an upwardly extending portion extending to the upper edge of the roadway and forming a boundary therefor, and having also a laterally extending flange remote 110 from its upper edge, said flange being provided at intervals with anchors extending downwardly and provided with locking means below the flange.

4. A metallic guard for defining the longitudinal edges of roadways, said guard having an upwardly extending portion extending to the upper edge of the roadway, and forming a boundary therefor, and provided at intervals with anchors remote from the upper edge of the guard, said anchors being adapted to lock in the base of the roadway, to hold the guards in place.

In testimony whereof I affix my signature in presence of two witnesses.

WILLIAM S. GODWIN.
